UNITED STATES PATENT OFFICE.

WILLIAM STEGEMAN, OF CHICAGO, ILLINOIS.

DESIGN FOR A MEAT-HOOK.

SPECIFICATION forming part of Design No. 33,506, dated November 6, 1900.

Application filed October 11, 1900. Serial No. 32,793. Term of patent 7 years.

To all whom it may concern:

Be it known that I, WILLIAM STEGEMAN, a citizen of the United States, residing at Chicago, in the county of Cook and State of Illinois, have invented a certain new and original Design for a Meat-Hook, (Case No. 1,) of which the following is a full, clear, concise, and exact description, reference being had to the accompanying drawings, forming a part of this specification.

The object of my invention is to provide a simple and advantageous design for a meat-hook.

In the accompanying drawings, Figure 1 is a front elevation of a meat-hook embodying my design, and Fig. 2 is a section taken on line 2 2 in Fig. 1.

The meat-hook illustrated comprises a body part A and a clip B, carried by the body part A. The body part A consists of a piece of rod or wire bent so as to form a loop 1 and also to form straight legs 2 2, extending downwardly from the loop 1 and having their lower ends turned in so as to form hooks 3 3. The legs 2 2 are arranged at inclinations to the median line of the device, so that they cross one another between their ends. The ends of the hooks 3 3 are pointed. The clip B is formed of a piece of wire or rod bent so as to form a yoke having a middle open portion 4, which receives the legs 2 2 of the body part A where such legs cross each other, and also bent so as to form thumb portions 5 5 on opposite sides of the middle opening 4.

What I claim as my invention is—
The design for a meat-hook substantially as illustrated and described.

In witness whereof I hereunto subscribe my name this 9th day of October, A. D. 1900.

WILLIAM STEGEMAN.
